(57) **CLAIM**

We claim the ornamental design for a twist and lock telescoping package, as substantially shown and described.

DESCRIPTION

FIG. 1 is perspective view of a twist and lock telescoping package shown my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a perspective view of the twist and lock telescoping package of FIG. 1 in a partly extended condition of use;

FIG. 9 is a front elevation view thereof;

FIG. 10 is a rear elevation view thereof;

FIG. 11 is a right-side elevation view thereof;

FIG. 12 is a left-side elevation view thereof;

FIG. 13 is a top plan view thereof;

FIG. 14 is a bottom plan view thereof;

FIG. 15 is perspective view of the bottom part of the twist and lock telescoping package of FIG. 1, shown separately to show aspects of the claimed design that are not visible when combined;

FIG. 16 is a front elevation view thereof;

FIG. 17 is a rear elevation view thereof;

FIG. 18 is a right-side elevation view thereof;

FIG. 19 is a left-side elevation view thereof;

FIG. 20 is a top plan view thereof;

FIG. 21 is a bottom plan view thereof;

FIG. 22 is perspective view of the top part of the twist and lock telescoping package of FIG. 1;

FIG. 23 is a front elevation view thereof;

FIG. 24 is a rear elevation view thereof;

FIG. 25 is a right-side elevation view thereof;

FIG. 26 is a left-side elevation view thereof;

FIG. 27 is a top plan view thereof; and,

FIG. 28 is a bottom plan view thereof.

(Continued)

The features of the claimed twist and lock telescoping package design are shown in solid lines in FIGS. 1-28, while the broken lines in FIGS. 1-28 depict portions of the twist and lock telescoping package that form no part of the claimed design.

1 Claim, 24 Drawing Sheets
